CLOCK OR SIMILAR ARTICLE

Theodore G. Daher, Stratford, Conn., assignor to
General Electric Company

Filed Mar. 31, 1971, Ser. No. 130,051

Term of patent 3½ years

Int. Cl. D10—01

U.S. Cl. D42—7

Fig. 2.

Fig. 1.

FIG. 3.

FIG. 4.

FIG. 1 is a front perspective view of a clock embodying my new design with a portion of the ornamentation between the clock face frame and the peripheral frame being omitted for convenience of illustration;

FIG. 2 is a top plan view thereof;

FIG. 3 is a front elevational view thereof;

FIG. 4 is a bottom plan view thereof;

FIG. 5 is a rear elevational view thereof; and

FIG. 6 is a side elevational view thereof.

I claim:

The ornamental design for a clock or similar article, as shown and described.
